VOLUME CONTROL SYSTEM FOR RADIO RECEIVING APPARATUS AND THE LIKE

Poul F. G. Holst, Riverton, N. J., assignor to
Radio Corporation of America, a corporation of
Delaware

Application October 21, 1932, Serial No. 638,838

7 Claims. (Cl. 250—20)

The present invention relates to volume control systems for radio receiving apparatus and the like, and has for one of its objects to provide an improved system of that character.

5 It is known that the human ear is less responsive to both high and low frequency sounds than it is to sounds in the middle register of the audio frequency range when the volume or amplitude of such sounds is at a low level. It is also commonly observed that there is usually some optimal loudness at which certain sounds, such as reproduced music or speech from a radio set or phonograph are most pleasing to listen to. The general effect is that music loses its body when reproduced at low volumes and speech sounds acoustically tubby when reproduced at high volumes. The cause for this effect can be traced to the variable frequency response of the ear to tones of different intensity.

20 When the volume control system of a radio receiver or similar apparatus such as an electric phonograph is so constructed that it does not change the frequency response of the apparatus, and most volume control systems have been built 25 with this aim in view, the reproduction usually sounds most natural when it is reproduced at the same intensity as it would be heard by an observer listening at the place where he would normally be located to hear the original performance. Because of a proper regard for the feelings of others, or possibly because of the listeners' own sensibility, radio apparatus and electric phonographs are very often operated at such 30 a volume adjustment that the sound intensity delivered by the reproducer is considerably less than that at which it would normally be heard. In such cases, the body of the music is badly lost.

40 If a volume control system is constructed so that the low frequency range of sounds is raised in almost an inverse ratio to the relative sensitivity of the ear in going from normal volume to the volume at which the sound is to be heard, a compensation results which makes up for the 45 different frequency sensitivity of the ear at the lower volume. Such a volume control is known as an "acoustically compensated volume control".

Accordingly, it is a further object of the present invention to provide an audio frequency volume control system for radio receiving apparatus and the like, adapted to compensate for deficiencies in the responsiveness of the human ear and to provide predetermined and relatively high degrees of compensation throughout certain portions of the audio frequency range of operation of

such apparatus, whereby the effect of the sound output therefrom may be in an apparent improved quality at low sound levels.

The application of this type of volume control system to a radio receiver presents certain 5 difficulties and requires the redesign of what have heretofore been regarded as adequate volume control systems. The so-called volume control means, in many radio receivers, is not strictly a volume control means, but a sensitivity control 10 means, since it regulates the radio frequency amplification to compensate for the variation in intensity of the voltage across the antenna and no definite relation exists between the position of the control and the output level of the reproduced 15 sound.

It is essential that a definite relation be established between reproduced sound output and volume control setting and that this level be maintained irrespective of the variation in intensity of 20 the voltage across the input of the receiver. This requirement necessitates a high gain radio frequency amplifier provided with an automatic sensitivity control capable of maintaining the voltage input to the demodulator substantially constant, 25 irrespective of the variation in signal intensity within the sensitivity limits of the receiver. The fulfillment of the requirement allows the use of a volume control in the audio channel of the receiver in which the angular rotation of the control bears a definite relation to the intensity of 30 the reproduced sound. With these conditions established, audio compensation can be incorporated in the receiver to give the required aural compensation for different output levels. 35

It is, therefore, a still further object of the present invention to provide an audio frequency volume control system of the character referred to, for compensating, simultaneously with variations in the adjustment of the signal amplitude 40 or volume level, certain portions of the audio frequency range of signals controlled thereby at the lower sound levels and to provide such signals at substantially constant average potential.

Broadcast receiver designs in the past have not 45 met these requirements because either no automatic sensitivity control was included in the design or the control employed was inadequate to maintain the signal to the required level.

In accordance with the invention, therefore, 50 one or more shunt impedance means are arranged to be connected gradually across an audio frequency signal transmission circuit through the medium of a volume control potentiometer device also connected in shunt with said transmission 55

circuit. The arrangement is such that the impedance means forms a frequency responsive variable load at predetermined tap points on the potentiometer device, so that the adjustments of 5 volume and of the loading are performed simultaneously in a predetermined relation by the operation of the volume control potentiometer device.

Suitable means is also provided to establish, at 10 the input terminals of the potentiometer device, substantially constant average signal input potentials. In a radio receiving apparatus, this may be provided through the medium of automatic volume control means. However, such means should be of an improved type adapted to provide 15 substantially a constant average output potential.

By providing a signal of substantially constant amplitude at the input terminals of the volume control device, it is possible to provide the volume control network, in which the volume control device 20 may be located, with a predetermined load, thereby to produce the necessary tone compensation at predetermined volume levels to effect the desired response characteristic definitely and under all conditions of operation. Furthermore, 25 as stated hereinbefore, a definite relation may be established between the setting or adjustment of the volume control device and the sound output controlled thereby irrespective of the variation in intensity of the signal voltage applied to the 30 input terminals.

By combining, in a radio receiving system, an adequate automatic volume control system and a compensated audio frequency volume control network, adjustments of volume level may have a 35 predetermined relation to tone compensation, and the adjustment of volume down to the lower levels of audibility may be made without causing any apparent change in the tone quality of the signals or sounds so controlled.

To summarize the foregoing, therefore, it may 40 be briefly stated that, in accordance with the invention, a volume control network is provided in an audio frequency signal transmission channel of a radio receiving apparatus or the like, and 45 having in connection with the network, means for providing input signals therefor of substantially constant average amplitude. The volume control network includes a tapped potentiometer volume control device connected in shunt with 50 the signal transmission circuit and electrically loaded at the tap or load points along its resistor element, whereby as the volume or signal level through the channel is varied by adjustment of 55 said potentiometer device, the loading is automatically applied gradually in shunt with the channel, while the signal input amplitude is held substantially constant. The electrical loading means includes circuit impedance elements arranged to have a certain predetermined frequency response characteristic operative to provide 60 a frequency variable shunt path or paths for portions of the potentiometer resistance.

With constant input potential from the signal source to the audio frequency signal transmission channel or volume control network, it will 65 be seen that the loading of the circuit may be made to have a predetermined relation to the volume level adjustment of the volume control device, thereby to provide a desired compensation 70 for that level. By providing such compensation and loading at various points along the volume control device, a predetermined compensation may be applied throughout the range of operation of said device, whereby a certain 75 portion or portions of the audio frequency signal

range may be affected to cause signals in said range or ranges to be attenuated or compensated to provide tone correction in the lower sound or signal output levels of operation.

The practical advantages of radio receiving apparatus having automatic tone compensation with volume control in conjunction with automatic volume control means, are readily appreciated when compared with the effect upon the quality of a received signal as the signal output of an ordinary radio receiver is reduced to the lower limit of what may be termed "comfortable room volume" by the usual volume control means. It will be noted that the tone of the reproduced signal from the ordinary receiver 15 is apparently reduced in frequency range and seems to lack both the low and the high frequency portions of the audio frequency range. As the signal level is further reduced in volume, the bass and the treble portions of the musical 20 range seem to disappear, leaving only the middle register in the signal sound range.

The invention, however, will be better understood from the following description when taken in connection with the accompanying drawing, 25 and its scope will be pointed out in the appended claims.

In the drawing, Figure 1 is a simple wiring diagram of a portion of an electrical signal transmission circuit provided with a volume control system embodying the invention.

Fig. 2 is a curve diagram illustrating a feature of the operation of the volume control system shown in Fig. 1;

Fig. 3 is a circuit diagram of a radio receiving apparatus provided with a volume control system embodying the invention; and

Fig. 4 is a curve diagram illustrating an operating characteristic of a preferred form of a volume control means employed in the circuit of 40 Fig. 3.

Referring to Fig. 1, 5-5 are the input terminals, and 6-6 are the output terminals of a signal transmission circuit 7, representing any audio frequency signal transmission channel or 45 circuit to the input terminals of which substantially constant average signal potentials are applied. Connected in shunt to the circuit, for the purpose of controlling the amplitude of the signals transmitted through said circuit and applied to the output terminals 6, is a volume control potentiometer device 8 having its resistor end terminals connected with the input terminals 5, and a movable arm or contact 9 connected, together with one of its end terminals, with the 55 output terminals 6, thereby to provide a conventional volume control system for a circuit of that character.

Referring to Fig. 2, this volume control system 60 operates in accordance with curve 10, plotted with reference to frequency in cycles per second, and signal transmission efficiency E, with varying frequency. This curve indicates that a device of this type will have a substantially straight frequency response characteristic and, accordingly, 65 for any adjustment of the volume control 8, by adjustment of the tap 9, will be substantially unaffected by variations in frequency of signals transmitted through the volume control network. While such apparatus, so operated, delivers the 70 signal output without actual change in fidelity, the effect upon the listening ear is that the fidelity has been noticeably changed.

In order to compensate for the deficiencies in 75 the response characteristic of the human ear, and

to provide a predetermined required sound intensity effect thereon, which is substantially constant throughout the audio frequency range at the lower sound levels, it is necessary to provide 5 a volume control system which, at the lower volume control adjustments for low level sound output, will have a fidelity or frequency response curve, indicative of its transmission efficiency at various frequencies of the nature of the curve 10 indicated at 11 in Fig. 2. From an inspection of this curve, it will be seen that a volume control system for compensating for the lack of responsiveness of the human ear to higher and lower frequency sounds, provides for accentuating said 15 sound ranges and attenuating the middle register, such as between 500 and 2000 cycles, to which the ear is more effectively responsive.

It will be appreciated that, in order to produce an audio frequency operating characteristic of 20 the character above described, a substantially constant signal is required upon the volume control network. The latter is of the shunt type 25 variably loaded to gradually bring into operation the shunt frequency variable impedance elements, all in a definite relation to the volume control adjustment, without which the system would be substantially ineffective. To this end, the potentiometer 8 is provided with at least one tap point 12 along its length, and preferably more 30 adjacent to the low potential end, and to this tap is connected a loading impedance Z, indicated at 13, having a certain predetermined variable frequency response characteristic and a certain predetermined relative impedance value within 35 the signal frequency range, in which signal attenuation is desired. This impedance value must be lower than and must bear a certain predetermined relation to the impedance of the low potential end or portion of the potentiometer device to which it is, through the tap point and 40 the low potential end, connected in parallel.

The loading impedance, indicated at 13, may include a resistance capacitance network and various circuit impedance elements so arranged 45 and related, as hereinafter described, that the impedance means may have a very low impedance value at the frequency, or within the frequency range, at which minimum response is desired, such as, for example, approximately 1500 cycles, 50 or between 500 and 2000 cycles. This value is with respect to the impedance of the low potential end of the potentiometer device between the tap point and the low potential terminal, that is, designating the high potential terminal of the 55 potentiometer device as 14 and the low potential terminal as 15, then that portion between the terminals 12 and 15.

In addition, the impedance means indicated at 60 13 preferably should have a relatively broad tuning response characteristic at the frequency at which minimum response is desired. With an arrangement of that character, the transmission response characteristic of the circuit and volume control means may have a certain low or room 65 volume adjustment such as at the tap point 12, by moving the slideable arm or contact 9 thereto, and be made to correspond to and have an operating characteristic which may be represented by the curve 11.

Furthermore, with a compensated volume control system of the above character, advantage 70 also may be taken of the fact that, at low volume control adjustments of the device 8, the output terminals 6 are connected by an impedance which 75 becomes gradually lower as the volume control

setting is reduced, thereby permitting succeeding devices or apparatus (not shown), to change their or its frequency response characteristic. For example, it will be appreciated, as apparent to one skilled in the art, that the leakage peak 5 in an audio frequency coupling transformer, if connected to the terminals 6, may be caused to increase appreciably, thereby causing the frequency response characteristic, in conjunction with changes in the adjustment of the volume 10 control device 8, to be accentuated and multiplied.

It should be noted that the curve 11 in Fig. 2 is that provided when the movable contact 9 is substantially at the tap point 12, while the curve 10 indicates the response characteristic when the 15 contact 9 is at the high potential end 14 of the volume control device. The response characteristic of the system for other adjustments of the contact 9 will be located between and conform to curves 10 and 11, approaching in shape more 20 nearly the one or the other of said curves to which they are more adjacent.

The volume control potentiometer device 8 should be, and preferably is, tapered in resistance from the high potential end 14 to the low 25 potential end 15 to produce variations in signal amplitude of volume, in a suitable manner, preferably being tapered in accordance with a logarithmic curve, thereby to produce equal changes in sound effect upon the ear for equal changes in 30 adjustment of the volume control device. A preferred form of response curve for a volume control device embodying the invention will be hereinafter described.

An additional advantage of a compensated volume control system of the character described, is that the range of operation includes a zero setting and is obtained by reason of the fact that the loading means for the circuit is so connected therewith, that it is not interposed in series 40 between the controlled circuit and the terminals of the volume control device. In the present example, it will be noted that the volume control tap 9 may be moved between the high potential end 14 and the low potential end 15, thereby to 45 change the volume adjustment from maximum to full zero. In a radio receiver, for example, this has the distinct advantage that the output of the receiver may be "cut dead" at such times as such adjustment is desired. 50

It will be noted that other tap points are provided on the resistor element 8 at 16 and 17, to which additional impedance elements may be connected in the same manner as impedance element 13 is connected to the tap point 12 and 55 for the same purpose. It has been found, however, that the circuit employing a single tap point is satisfactory.

The combination of a shunt volume control potentiometer device with shunt impedance devices or means connected with tap points on the potentiometer device and having a constant average signal input potential applied to the circuit has the advantage that not only may the tap point or points be gradually connected effectively to the circuit, but the circuit involves no series impedance elements through which all components of the signal must pass. It is provided only with shunt impedance means each of which pass only such signal energy as it is 65 designed to compensate or attenuate. Signals within other frequency ranges are less affected by the effective impedance of the compensating or attenuating means.

Referring now to Fig. 3, 18 indicates a radio 75

receiver provided with an automatic volume control system and having input terminals 19 connected with suitable energy collecting means, such as an antenna 20 and ground connection 21, and having output terminals 22 connected with a audio frequency signal channel 23 through the medium of an audio frequency amplifying or detecting tube 24.

The signal potential applied to the tube 24 and, therefore, to the audio frequency signal channel 23 from terminals 22, may be indicated at E₂ and is substantially constant in response to a variable signal potential E₁, applied from the collecting means to the input terminals 19.

Any suitable receiving apparatus may be employed and any suitable automatic volume control system may be provided in conjunction therewith to deliver to the input end of the audio frequency signal channel substantially a constant average signal potential. With an arrangement of that character, the audio frequency tube 24, which may be the audio frequency detector, is caused to receive a constant signal potential whereby the volume control means for the apparatus may be placed wholly in the audio frequency channel.

In the present example, the tube 24 may be considered as a detector tube and the audio frequency signal channel 23 is included in its anode circuit. Accordingly, the one side of the signal channel is connected with a source of anode potential (not shown) through an audio frequency coupling impedance or choke coil 25. The circuit is also provided with the usual radio frequency filter circuit indicated by the filter devices 26.

Connected in shunt with the audio frequency transmission channel 23 is a volume control potentiometer device 27 having input terminals 28 and a variable contact element 29. A tap for a shunt impedance load is provided at 30, more adjacent to the low potential end of the potentiometer device, and is connected with the low potential end of said device through a series choke coil or inductive reactance 31 and a condenser or capacitive reactance 32, forming a tuned circuit in shunt with the low potential end of the potentiometer device. The variable contact member 29 and one terminal 28 of the potentiometer device are connected with the primary 33 of an output transformer 34 through a tone control network 35 comprising a series choke coil 36, a shunt condenser 37, and a potentiometer device 38 interconnected in such a manner that the choke coil may be connected in series with the transmission circuit and the condenser in shunt therewith, or both may be effectively removed from the circuit gradually by operation of the potentiometer device.

This tone control network per se, forms no part of the present invention and, therefore, is believed to require no further description. For example, it may be of the type shown in Fig. 2 of Bierwirth Patent, 1,997,762, and described and claimed therein.

It will be seen that the volume control potentiometer device 27, being of the shunt variable contact type, is adapted to provide a variable output impedance with respect to the primary 33 of the output transformer 34. By this means, a variation in the performance of the tuning between the leakage impedance and the shunt stray capacity of the secondary 39 may be provided to assist in the compensating action of the volume control device.

However, the main compensation in the volume control device is provided by the shunt impedance means, comprising the impedance elements 31 and 32. For tone compensation, whereby the sound intensity upon the listening ear is caused to be substantially constant over the entire audio frequency range at reduced volume levels, a value of substantially 30,000 ohms total for the potentiometer device 27 has been found to be satisfactory in a circuit of the character shown, comprising an output circuit for an audio frequency tube in connection with the primary of an audio output transformer. The tap point 30 in a system of that character is preferably placed substantially at 6000 ohms above the low potential end of the potentiometer device and the impedance elements 31 and 32 may have values from 50 to 80 millihenries and .5 mfd. respectively, with a total ohmic resistance in the choke coil 31 of substantially 520 ohms.

It will be seen that, with the tap 29 of the potentiometer device at the load point 30, an ohmic impedance of 520 ohms is then placed in shunt with 6000 ohms. The condenser 32 and the choke coil 31 tune broadly to frequencies in a signal range to be attenuated, such as the range including 1500 cycles, whereby the operating response may correspond to the desired output curve indicated at 11, in Fig. 2. Since the condenser and choke coil are tuned to such a range of frequencies, it will be seen that signals in said range will be highly attenuated because of the low impedance, (520 ohms), of the shunt path from the tap or load point 30 to the low potential side of the circuit.

More specifically, the impedance ratios provided in the volume control network of the present example are such that the middle register of the audio frequency range to which the ear is more sensitive, are attenuated approximately 48 times with respect to the higher and lower frequency portions of the audio frequency range. This will be seen from a consideration of the ratio of the selected impedances when the variable contact 29 is located, for maximum attenuation, opposite the fixed tap connection 30, in which position the ratio of impedances are approximately 520 to 24,520, or 1:48, for the middle register of the audio frequency range to which the impedance means 31—32 is responsive. This is disregarding the shunt impedance of 6000 ohms across the impedance means 31—32.

Within the signal range to be attenuated, substantially the only impedance in circuit between the tap point 30 and lower end of the volume control network is the ohmic resistance of the inductance 31 and the higher resistance of the lower section of the volume control device. The inductance is arranged to have approximately 520 ohms and thereby to provide the desired ratio between it and the impedance of the shunted portion of the potentiometer device. In an inductance provided for a circuit as shown in the drawing, resistance wire is used for the winding to provide the desired resistance at the desired inductance of 80 millihenries.

Signals outside the attenuation range are much less attenuated by the impedance means 31—32 for the reason that the inductance 31 and condenser 32 are less effective, and the impedance ratios are substantially those provided by the two sections of the potentiometer device in the ratio of 6000 to 24,000 or substantially 1 to 5. Therefore, the signals outside the range of signals to be attenuated are reduced only five times as com-

pared with substantially 48 times for the range above described.

The ratio of the impedance values provided by the potentiometer device and the shunt impedance network may be considered in the circuit in which it is employed, by assuming a certain output impedance for the tube or device to which it is coupled.

For example, referring to Fig. 3, the output impedance of the tube 24 may be considered as 20,000 ohms, then with a resistance of 30,000 ohms total for the potentiometer device 27, and a resistance of 6,000 ohms between the tap point 30 and the low potential terminal 28, an impedance 15 of 520 ohms for the network 31-32 has been found to provide a desired attenuation of signals within the range to which the network is tuned, such as between 500 and 2000 cycles. Considering the output voltage delivered to the output circuit 20 connected with the potentiometer contact 29 when the latter is at the point of maximum compensation 30, said output voltage will be equal to

$$\frac{500}{44,500} \text{ or substantially } \frac{1}{99}$$

which is the ratio of the output to input potential, the input potential being supplied through the impedance of the tube of 20,000 ohms plus the impedance of the potentiometer device between the high potential terminal 28 and the tap point 30 of 24,000 ohms, and the impedance between the tap point 30 and the low potential terminal 28 of substantially 500 ohms.

The corresponding impedance ratios for the signal potentials outside the range of compensation, such as the high frequency and the low frequency signals may be expressed as

$$\frac{6,000}{50,000} \text{ or } \frac{1}{8.33}$$

approximately. The compensation provided by the system at the tap point 30 may thus be expressed as

$$\frac{99}{8.33}$$

or substantially 12. Subtracting the initial compensation of 1, this provides a compensation of substantially 1100%.

This maximum compensation may be compared with the compensation at another point, for example at a point mid-way between the high potential terminal 28 and the point of maximum compensation 30, by the same procedure. For example, the compensation for the frequency range to be attenuated may be represented by the impedance ratio of

$$\frac{12,500}{44,500}$$

while the compensation outside this range at the high and low frequency ends of the audio frequency range may be represented by the fraction

$$\frac{18,000}{50,000}$$

Comparing these two fractions, the maximum compensation may be determined as 1.40, or 40% compensation as compared with the 1100% compensation at the point 30.

From the above it will be seen that very little compensation is provided at the higher volume levels, as is desirable for reasons hereinbefore

given, but that the compensation is relatively high at the maximum point, as is also desirable and necessary to obtain the proper effect upon the ear at low sound output levels.

In considering compensation for acoustical effects in a volume control system of the present invention, it is necessary to determine at what sound level, or wattage output the maximum compensation should be employed to produce the desired effect upon the ear, for the reason that, as has been hereinbefore explained, the ear is less sensitive to sounds in the high and low frequency ranges at low sound levels than it is at the higher levels above what may be termed normal room volume.

Accordingly, in providing a volume control system embodying the invention, the volume control device is so designed that the tap compensating points may be provided at positions to which the device is adjusted for sound levels at which compensation is most effective. For example, if a maximum output of 20 watts is available, the maximum compensation for tone or acoustic effects is arranged to be provided at a sound output of substantially one watt or less in a radio receiving apparatus, although other ratios for radio receivers and other apparatus are necessary to meet differing operating conditions.

From the foregoing description, it will be seen that by changing the constants of the circuit elements 31 and 32 and by changing the tap points or increasing the number of tap points as in the circuit shown in Fig. 1, other operating characteristics may be given to the volume control action.

In itself, the volume control action is preferably logarithmic, whereby the ear may perceive equal increases in volume level for an equal degree of movement of the control element of the volume control device. It has been found in a volume control system that the action of the volume control device is preferably logarithmic above and below each tap point and, in accordance with the invention, a volume control potentiometer device, having an operating characteristic represented by the curve 40 shown in Fig. 4, is preferred. Referring to Fig. 4, this curve is plotted between resistance in ohms and rotation of the control element of the potentiometer device. It will be noted that the curve is logarithmic in shape, between the zero resistance point indicated at 41 and a point 42 representing the tap point 30 of the device shown in Fig. 3. It is also logarithmic between point 42 and a point 43, or maximum resistance point. Resistance values between the various terminals are indicated on either side of the curve for a better understanding of the operation of the potentiometer device.

The use of the double logarithmic taper in a volume control potentiometer provided with shunt loading for the purposes hereinbefore described is necessary, for the reason that when the movable contact of the potentiometer device reaches the loading point whereat maximum compensation is obtained, the impedance from the movable contact to the low potential side of the audio frequency transmission circuit is no longer determined solely by the portion of the potentiometer resistor between said tap and the low potential side of the circuit. It is then determined also by the loading connected with the tap point, and adjustments of the volume control device below the tap point take from a potential existing across terminals 30 and low potential terminal 28, as

determined by the loading. Accordingly, it has been found desirable and effective in operation, to provide a second logarithmic taper from the tap point to the low potential side of the potentiometer device for operation in accordance with the curve shown in Fig. 4, when a single tap point is provided.

As is well known and understood, by logarithmic taper is meant that changes in resistance, for example, between the movable tap 29 and a terminal of the potentiometer device, such as the high potential terminal 28, as the contact 29 is moved away from said terminal along the resistance element of the device toward the opposite terminal, is at first rapid and then gradually less for equal distances moved along the resistance element. The decrease in change of resistance for equal distances vary in accordance with a logarithmic curve and for the purpose of producing a signal output effect of a corresponding equal increment or decrement character.

In the circuit described above, the attenuation of voltage, with the arm 29 at the tap 30, is -14DB with the compensation circuit 31-32 disconnected. Connecting the compensation circuit results in an additional attenuation of -34DB for frequencies in the region of 1000 cycles (500-2000 cycles). The voltage output at 100 cycles is up 16DB from that at 1000 cycles at the point of maximum compensation.

Reducing the volume control setting below the point of maximum compensation has little effect on the shape of the voltage frequency characteristic of the volume control circuit. Care must be exercised in determining the value of the tapped portion of the volume control in order that subsequent circuit constants are not effected when the volume control is adjusted to positions below the point of maximum compensation.

Referring again to Fig. 3, means are provided between the input end of the audio frequency transmission channel and the volume control device 21 for controlling the transmission efficiency of the circuit to reduce the effect of hiss and high frequency noises when receiving under adverse conditions.

This means includes two condensers 44 and 45 arranged to be selectively connected in series with one side of the transmission channel by a selector switch 46. The condensers have widely different impedance values, the condenser 44, for example, having a value suitable for attenuating certain portions of the high frequency end of the range, and the condenser 45 being adapted to transmit freely all signals within the audio frequency range for greater fidelity of operation.

From the foregoing description, it will be seen that a volume control system, in accordance with the invention, provides for loading an audio frequency transmission circuit by shunt signal attenuating means, gradually bringing such attenuating means into operation successively to load the circuit within predetermined frequency ranges of operation at lower levels of audibility and that this control is effected by simple means in a circuit supplied by signals of constant average amplitude and amplified thereby to produce a response characteristic which, regardless of variations in input signal potentials and similar operating conditions of the apparatus, may produce a sound intensity effect upon the ear, of an adjustment of volume level only, without apparent change in fidelity or tone quality.

The problem of using the acoustically com-

pensated volume control with a phonograph is much simpler. Most records are recorded with the average intensity maintained close to some standard level and any adjustment of the frequency compensation for one record holds for practically all other records. The volume control may, therefore, be compensated without difficulty as the input signal is automatically controlled in volume by the record.

It will be understood that various modifications within the conception of those skilled in the art are possible without departing from the spirit of my invention or the scope of the claims.

I claim as my invention:

1. In an audio frequency volume control system, a tapped volume control potentiometer device comprising a resistor element having at least two resistor sections, means providing a fixed tap connection between said sections and a variable contact movable along and in connection with said element, frequency discriminating impedance means connected in shunt with one of said sections through said tap connection, said means comprising a single inductor and a single capacitor only in series, and an output circuit therefor connected with said variable contact.

2. In a radio receiving apparatus, the combination of a detector having substantially a constant audio frequency signal output, an audio frequency signal transmission circuit following said detector for transmitting audio frequency signals therefrom, a volume control network in said circuit and including a potentiometer volume control device having a resistor element comprising two differing resistance sections and a tap connection between said sections, one section being less than one half the resistance of the other section, an impedance means connected with said tap connection across the lower resistance section of said resistor element, said impedance means including a series connected inductance and capacity tuned to a predetermined range of signal frequencies and having within said range of frequencies an impedance relatively lower than the impedance of the resistance element section across which it is connected, and a variable contact element for said potentiometer device for controlling the load applied to said circuit by said impedance means.

3. In a radio receiving system, automatic volume control means for providing substantially constant average signal amplitude, an audio frequency signal transmission circuit for receiving signals controlled by said automatic volume control means, and audio frequency volume control means including a tapped resistor in shunt with said circuit, an output circuit having a variable tap connection with the resistor substantially throughout its length for volume control, a reactance network connected in shunt with a portion of said resistor including the low volume end thereof, said portion including less than one third of the total resistance of said resistor, said network and said portion of said resistor having a predetermined impedance ratio whereby tone compensation is provided simultaneously with volume control, the compensation increasing as the volume control tap connection is moved to a position to reduce the volume.

4. In a radio receiving apparatus, the combination of an audio frequency signal transmission circuit, a volume control network in said circuit including a potentiometer volume control device having a resistor element comprising two differing resistance sections and a tap connection

- between said sections, one section having a resistance at least lower than one half the resistance of the other section, an impedance means connected with said tap connection across the 5 lower resistance section of said resistor element, said impedance means including a series connected inductance and capacity tuned to a predetermined range of signal frequencies and having within said range of frequencies an impedance relatively lower than the impedance of the 10 resistance element section across which it is connected, and a variable contact element for said potentiometer device for controlling the load applied to said circuit by said impedance means.
- 15 5. In an audio frequency volume control system, a control device including a shunt variable resistor element, a tone compensating reactance means connected in shunt to a fixed portion of said element less than the whole, said means being tuned to provide a minimum impedance to 20 signals within a predetermined audio frequency range, wherein attenuation of said signals is de-
- sired, and variable tone control means connected to additionally control signals transmitted through said control device independently thereof in a differing frequency range.
6. In an audio frequency volume control system, 5 a control device including a shunt variable resistor element, a tone compensating reactance means connected in shunt to a fixed portion of said element less than the whole, said means being tuned to provide a minimum impedance to 10 signals within a predetermined audio frequency range, wherein attenuation of said signals is desired, and a second control device associated in circuit with said first device for independently controlling the frequency characteristic of signals 15 in a differing audio frequency range.
7. In an audio frequency signal transmission network, volume control means having fixed compensation for one frequency range and variable tone control means connected therewith responsive to signals in a differing frequency range. 20
